UNITED STATES PATENT OFFICE.

GEORGE WILLIAM ZASTROW, OF BALTIMORE, MARYLAND.

MACHINE FOR TREATING PINEAPPLES.

SPECIFICATION forming part of Letters Patent No. 735,649, dated August 4, 1903.

Application filed March 4, 1903. Serial No. 146,039. (No model.)

To all whom it may concern:

Be it known that I, GEORGE WILLIAM ZASTROW, a citizen of the United States, residing at Baltimore, State of Maryland, have invented 5 certain new and useful Improvements in Machines for Treating Pineapples, of which the following is a specification.

This invention relates to a machine for treating fruit such as pineapples to prepare them for canning.

I have shown my improvement as applied to the type of machine shown in my Patent No. 482,493, dated September 13, 1892; but it will be understood that my invention may be 15 employed in other types of machines.

The object of the present invention is to provide a device which will automatically feed the pineapple or other article to the cutter at a uniform speed, and thereby insure that the 20 slices will be of a uniform or equal thickness.

To this end the invention consists in the novel features of construction and combination of parts hereinafter described and claimed.

25 The invention is illustrated in the accompanying drawings.

Figure 1 illustrates a side elevation of a machine provided with my improved feed device. Fig. 2 illustrates a top plan view of 30 same, and Fig. 3 illustrates a vertical section on the line 3 3 of Fig. 1.

The letter A designates the bed-piece of the machine, which consists of a hollow casting with a longitudinal slot A' in its top, and 35 is supported on suitable legs B. A carriage C rests on top of the bed-piece A and has a guide-rib C', fitting the slot A', which forms a slideway for it, and said carriage has a rack D, fastened to said rib and contained within 40 the bed-piece A. A segment-gear D' engages said rack and is worked by a lever E on its shaft. By this means the carriage may be reciprocated. A circular head F is supported 45 on the front side of the carriage and carries a pin G, which projects from said head, and said head and pin are movable horizontally with the said carriage. A standard J is stationed at a suitable place on the bed-piece A, and this standard carries a rotary head L, 50 having the form of a pulley, around which a belt (not shown) may be run to revolve said head. The particular construction and ar-

angement of this head are not a part of the present invention and are shown in my said former patent. A tube N extends from the 55 head L in a direction parallel with the bed-piece A, and the bore of said tube is in line with the central bore through said head and receives the pineapple or other article after it passes through said head and guides the 60 same toward the slicing device. The tube N extends to the rear end of the machine, where it is supported by a standard Q, fixed upon the bed-piece A, and between said standards J and Q the tube N is provided with a longitudinal slot h in its upper side to give access thereto.

A shaft R is mounted at one side of the machine in suitable bearings R' and carries at one end a circular disk S, which latter in 70 turn carries suitable knife-blades T, which revolve across the end of the tube N. A pulley V is secured on the end of the shaft R, by means of which the shaft, circular disk, and knife-blades are revolved. A sleeve W 75 is supported on the shaft R and is adapted to be moved longitudinally thereon, and at one end said sleeve is provided with an operating-lever w, which projects at right angles to said sleeve and over the slot h in the tube 80 N. A web w' connects the sleeve and operating-lever and gives strength to the latter. An arm w² projects downwardly from the operating-lever w, and said arm in the present instance is curved inwardly and projects 85 through the slot h into the tube N, as clearly seen in Fig. 3. A cord x is secured at one end to the sleeve W and passes over a pulley x', which latter is attached to the frame 90 of the machine, and the lower pendent end of said cord carries a weight x². A receptacle x³ receives the sliced pineapple as it is cut by the knife-blades.

In operation the arm w² takes in the tube 95 behind the pineapples y, which have been previously shaped and prepared by passing through the rotary head L, and the weight x² draws the sleeve, lever, and arm toward the knife-blades T at the end of the tube and slices the pineapple as it is automatically fed 100 forward. It will be seen that the pressure of the arm w² against the pineapples in the tube is regulated by the size of the weight, and as long as the same weight is used the pressure

- against the pineapples is always the same and the pineapples are fed through the tube to the knife-blades at a uniform rate of speed. When the arm w^2 reaches the end of the slot 5 h , the operator raises the lever w and returns it to the starting-point by sliding the sleeve on the shaft R and inserts the arm behind another row of treated pineapples to be sliced.
- 10 It is obvious the machine may be used for treating articles other than pineapples.
- Having thus fully described my invention, what I claim as new, and desire to secure by Letters Patent, is—
- 15 In a device of the class described the combination of a shaft; a tube at one side and extending in a direction parallel with said shaft and provided with a slot in its upper side; a circular disk carried on said shaft

and adapted to be revolved across one end of 20 said tube; a rotary head at the other end of said tube; a sleeve movable on said shaft and having a lever which projects at right angles to and extends over the slot in said tube, said lever having a downwardly-projecting arm which enters the slot of said tube; a weight and a flexible device connecting the weight and said sleeve whereby to cause the downwardly-projecting arm to move through the tube between the rotary 25 head and the circular disk.

In testimony whereof I affix my signature in the presence of two witnesses.

GEORGE WILLIAM ZASTROW.
